UNITED STATES PATENT OFFICE.

ADAM I. KLOCK, DECEASED, LATE OF ST. JOHNSVILLE, NEW YORK, BY LIBBIE M. KLOCK, ADMINISTRATRIX, OF ST. JOHNSVILLE, NEW YORK, ASSIGNOR OF ONE-THIRD TO B. F. KLOCK AND ONE-THIRD TO R. W. KLOCK, BOTH OF SCOTIA, NEW YORK.

MACHINE FOR APPLYING COATINGS.

1,284,708.

Specification of Letters Patent. Patented Nov. 12, 1918.

Application filed May 23, 1918. Serial No. 236,223.

To all whom it may concern:

Be it known that ADAM I. KLOCK, deceased, late a citizen of the United States, and a resident of St. Johnsville, in the 5 county of Montgomery and State of New York, invented new and useful Improvements in Machines for Applying Coatings, and that LIBBIE M. KLOCK, the duly constituted administratrix of the estate of ADAM 10 I. KLOCK, deceased, does hereby declare the following to be a full, clear, and exact description of the said invention of said deceased, ADAM I. KLOCK, and such as will enable others skilled in the art to which it 15 appertains to make and use the same.

The present invention relates to that class 20 of machines designed primarily for applying amalgam to mirrors although the use thereof is not limited to any particular lines. The principal object of the invention is to provide a machine of the class specified which may be constructed and operated at comparatively little cost, yet one which will be rapid and efficient in operation. Other 25 objects of the invention will appear as the description proceeds with reference to the accompanying drawings which form a part of this specification and in which:

Figure 1 is a side elevation of the improved machine with parts of the upper and lower tracks broken away and in section;

Figs. 2 and 3 are detail vertical transverse sections on the planes of the lines 2-2 and 3-3 of Fig. 1;

Fig. 4 is an end elevation partly in section, the two sets of tracks being swung to a horizontal position;

Fig. 5 is a horizontal section on the plane of the line 5-5 of Fig. 1 but showing the 40 tracks in a horizontal position for the sake of clearness;

Fig. 6 is an enlarged side elevation of the brake actuating lever and Fig. 7 is a horizontal section thereof on the plane of the line 7-7 of Fig. 6;

Fig. 8 is an enlarged vertical section of the amalgam tank and the car which carries the plate to be coated;

Fig. 9 is an enlarged side elevation of 50 the amalgam tank; and,

Fig. 10 is a detail horizontal section, on substantially the plane of the line 10-10 of Fig. 9.

In the drawings above briefly described, the numerals 1 have reference to a pair of vertically disposed side frames preferably formed for the most part of angle iron, the upper ends of said frames being connected by transverse bars 2 while a transverse rod 3 extends between the base bars 4 of the two frames and is carried by plates 5 adjustable longitudinally of said base bars and capable of being held in any position by screws 6 which are received slidably in the longitudinal slots 7 with which the bars 4 are provided. It is the function of the rod 3 to limit the tilting movement of the upper and lower tracks yet to be described.

Each side frame 1 is provided with a horizontal plate 8 disposed about midway between its upper and lower ends and secured to its side bars, said plates revolubly supporting a horizontal transverse shaft 9 upon which bearings 10 are clamped by set screws or the like 11 (see Figs. 4 and 8), 75 said bearings being carried rigidly between the upper and lower tracks 12 and 13 and disposed midway the lengths of said tracks. Both sets of tracks are thus mounted for tilting movement and are adapted to move 80 between the positions shown in Figs. 1 and 5. The tilting of the tracks toward the vertical is limited by the rod 3 which may be adjusted to any required extent, whereas stops 14 (see Fig. 4) prevent the movement of 85 the tracks beyond a horizontal position.

The upper and lower pairs of tracks are spaced apart by blocks or the like 15 and although said tracks could well be of any preferred formation, they are preferably constructed of angle iron. Upper and lower cars 16 and 17 travel respectively on the tracks 12 and 13, said car 17 serving only as a weight for overbalancing 16, the two being connected by a cable 18 passing around pulleys 19 carried by transverse bars 20 which connect the upper ends of the several tracks. Another cable 21 is connected to the lower end of the car 16 and passes around the pulleys 22 mounted on transverse bars 23 by 95 100

which the lower ends of the tracks are connected, said cable being wound at its other end on a drum 24 which is mounted rotatably on one end of the shaft 9. It will thus 5 be seen that when cable 21 is wound on said drum, the car 16 will be moved toward the front of the tracks 12, whereas the car 17 will travel in the reverse direction to return 10 16 to its initial position, when the driving means of the drum are released.

Any suitable arrangement of parts could well be employed for rotating drum 24 but one end thereof is preferably provided with a spur gear 25 meshing with a similar gear 15 26 on a short transverse shaft 27 which is supported rotatably by one of the plates 8, a two-part clutch 28 being provided for driving said shaft, one part of said clutch having a suitable operating handle 29 (see 20 Fig. 3 for details). By the provision of the clutch 28, the shaft 29 may be rotated to so turn the gears 26 and 25 as to rotate the drum 24 to wind cable 21 thereon, thus moving the car 16 toward the front end of 25 its tracks 12. When, however, the clutch is released, the weight of the car 17 comes into play to return car 16 to its previous position, the tracks being then inclined as shown in Fig. 1. This return movement 30 of the car 16 takes place after the plate to be coated has been placed thereon, and in order to prevent the parts from moving too rapidly, a brake 30 is provided to control the drum 24.

35 Brake 30 may be of any suitable construction but is preferably in the form of a short vertically disposed lever having a lateral offset 31 by means of which it is fulcrumed on a longitudinal rod 32 which is supported 40 by one of the side frames 1, immediately above the plate 8 (see Figs. 1 and 2). Brake 30 is applied by a coiled spring 33 which exerts its tension outwardly on the upper end thereof, and for the purpose of releasing 45 said brake, a link 34 extends outwardly therefrom and is pivoted to a horizontally swinging hand lever 35 which is fulcrumed to a vertical bracket or the like 36 secured at one end to one of the plates 8 and at 50 its other end to an angle iron bar 37 above said plate, each frame 1 being provided with one of said bars 37 for a purpose to be described.

For locking the lever 35 in position to 55 release the brake 30, a dog 38 is pivoted to one of the side bars of the frame 1 upon which said lever is mounted, said dog passing through openings in the lever and being normally moved by a spring 38^a into engagement with a shoulder 38^b thereon, the lever being preferably of the hollow construction shown in Figs. 6 and 7, so that a rod 39 may slide therein for the purpose of releasing dog 38 when it is required that spring

33 shall apply the brake 30. It is to be 65 understood, however, that the force with which the brake is applied may be controlled by the lever 35.

Although the upper and lower tracks 12 and 13 could well be adjusted by swinging them around the shaft 9 by hand, gear segments 40 are preferably secured to said tracks as shown in Figs. 1 and 4, said segments meshing with pinions 41 on a transverse shaft 42 having a crank or the like 43 70 at one end. Turning of the crank thus swings the tracks to and between the required inclined positions and a horizontal position. The segments 40 are preferably formed with openings 44 through which 75 locking bolts 45 may project to hold the tracks in adjusted position, said bolts being slidably mounted in any preferred manner and being preferably connected at their inner ends with a vertical rod 46 by means of inclined links 47 (see Figs. 1 and 4). The lower end of rod 46 is pivoted to a crank arm 48 on a transverse rock shaft 49 having a pedal 50 for operating it, a suitable spring 51 being employed for normally so positioning said rock shaft as to project both 80 bolts 45. When the pedal 50 is depressed, however, the bolts are retracted, whereupon rotation of crank 43 will swing the tracks 12 and 13 as required. 95

95 A tank 52 is provided for containing the amalgam or other coating to be applied, said tank having a reservoir compartment 53 in its upper end and a working compartment 54 in its lower end, the two being in communication when valve 55 is opened as shown in Fig. 8. Openings 56 establish constant communication between the working compartment 54 and a transversely extending spout 57 over the straight upper edge 100 on which the coating material is delivered to the plate or glass 58 carried by the car 16, electric heaters 59 being preferably employed for heating the contents of the tank 52 in order that they may flow freely. 105

110 A bar or other suitable spring-raised member 60 extends across the spout 57 and is rockably mounted therein, being adapted to be forced downwardly into the coating fluid to cause the same to overflow from the delivery end of the spout, this operation being facilitated by a pusher bar 61. For depressing bar 60, crank arms 62 are carried by a rock shaft 63 which extends through the sides of the spout 57, the outer end of said 115 shaft having an adjustable arm 64 operated by a longitudinal strip or track 65 carried by one edge of the car 16. The pusher bar 61^a is carried by arms 66 depending from a rock shaft 67 which is parallel with shaft 120 63, the end of the shaft 67 remote from the arm 64 being provided with an adjustable crank arm 68 for engagement with a second

track or strip 69 on the edge of car 16 remote from 65.

Track 69 also operates a third adjustable crank arm 70 (see Fig. 9) said arm serving 5 to operate a lever 71 which is fulcrumed on one side of the tank 52. A link 72 rises from lever 71 and is pivoted to a lever 73 which is connected with valve 55 by means of a vertical link 74 (see Figs. 4, 8 and 9).
 10 By the arrangement of parts just described, including the three adjustable arms 64, 68 and 70, upward movement of the car 16 under the action of the weighted car 17 will open valve 55 to supply a quantity of 15 coating fluid to the compartment 54, from the spout of which it is caused to overflow by depression of the member 60 and outward feeding of the pusher bar 61^a. The fluid is thus forced over the edge of the spout 20 onto the plate or glass 58 as the latter travels beneath said spout, and as the car moves upwardly, the valve 55 is gradually opened a greater amount and the bars 60 and 61^a slowly moved. This operation is caused by 25 the fact that the tracks 65 and 69 are divergent in respect to the tracks 12 upon which the car 16 travels as will be clear from Figs. 1 and 8. By gradually opening the valve a greater amount, it is insured 30 that sufficient coating fluid shall be supplied to the working compartment 54 to compensate for that forced over the edge of the spout 57, and the positioning of the aforesaid tracks 65 and 69 causes the bars 60 35 and 61 to continue moving throughout the period of time taken for the car 16 to travel thereunder.

The car 16 may be constructed as occasion may demand but is preferably formed 40 as shown in Figs. 1, 5 and 8. A pair of axles 75 extend between the wheels 76 which travel on the tracks 12, and a pair of longitudinal side bars 77 are supported by said axles, said side bars adjustably supporting the 45 tracks 65 and 69 by means of set screws or the like 78. Two longitudinal reach bars 79 are secured at their ends to the axles 75, and immediately above said reach bars, two supporting bars 80 are provided to receive 50 thereon the plate to be coated, said bars 80 being supported from the reach bars 79 by coiled springs 81 which permit said bars 80 to move downwardly according to the thickness of the plate 58. Upward movement of 55 the bars 80, however, is limited by screws 82 which pass slidably through the reach bars 78 and are threaded into bars 80, said screws preferably passing through the springs 81. An undercut transverse bar 83 is provided at 60 the rear or upper end of the car 16 to receive thereunder one end of the plate 58 as shown in Fig. 8, the lower edge of said plate being engaged by the heads 84 of pins 85 which rise from the ends of a clamp 86

which is adjustable along the reach bars 79 65 and may be locked in any position by the set screw 87. The clamping means for the plate or glass 58 is thus rendered adjustable so that the latter may be of any required length. 70

The tank 52 may be mounted in any preferred manner but said tank is preferably adjustable longitudinally of the machine as well as vertically. The sides of the tank in question are provided with laterally extending pins 88 (see Figs. 9 and 10), said pins being received rockably in slide bars 89 whose outer ends are received between vertically spaced horizontal bars 90 (see Figs. 1 and 4), said bars 90 being adjustable vertically in unison by means of a pair of vertical screws 91 mounted at their lower ends upon the bars 37 previously described. Rotation of these screws will thus adjust the tank 52 vertically. For shifting said tank 85 longitudinally horizontal screws 92 shown in Fig. 1 are threaded through the outer ends of the slide bars 89.

Ears 93 extend forwardly from the side frames 1 adjacent the upper bars 90 and 90 support the transverse rod 94 upon which a pair of longitudinally slotted links 95 are pivoted, screws 96 being passed through the slots of said links and threaded into the sides of the tank 52. Tightening of these 95 screws, after adjusting the tank 52 as required, will hold said tank in proper position. Furthermore, by loosening the screws in question, the tank may be inclined if occasion should so demand. 100

It may here be stated that a certain coaction exists between the adjustable stop means 3—5—6 for the tracks 12 and 13, and the adjustability of the tank 52, in that when applying certain coating fluids, it is necessary to incline the plate to be coated a greater amount in order that the fluid may properly run as it is applied. When such adjustment is made, it is also necessary to adjust the tank by the means described. 105 110

In operation, the two sets of tracks 12 and 13 are swung to a horizontal position by first depressing the pedal 50 to release the locking bolts 45 and then turning the crank 43. The pedal is then released so that the bolts 115 automatically lock said tracks in the position at which they have been set. The brake 30 is now released, and by means of the crank 29 and clutch 28, the drum 24 is operated to move the car 16 to the front end of tracks 12, whereas the balancing car 17 will be then moved to the rear ends of its tracks 13. This having been done, the plate 58 is clamped on the car 16. The brake 30 has by this time been again applied and the 120 tracks are then adjusted to the inclined position permitted by the rod 3, said tracks 125 being then locked by the bolts 45. Brake 30

is now again released and since car 17 is of greater weight than 16, the former will move downwardly to pull the latter upwardly beneath the tank 52. As this takes place, the two tracks 65 and 69 so operate the arms 64, 68 and 70 as to open the valve 55 and cause the bars 60 and 61 to start the flow of coating fluid from the spout 57 onto the plate 58. As car 16 is thus traveling upwardly, the inclination of the tracks 65 and 69, in respect to the tracks 12, causes the valve 55 to be gradually opened a greater amount while the bar 60 is caused to continue in its downward movement. Similarly the pusher bar 61 continues to move outwardly to force the coating fluid over the edge of the spout and onto the plate 58. When the latter has been completely coated by passage of car 16 under tank 52, the tracks 12 and 13 are again moved to a horizontal position and the coated plate is removed, whereupon the machine is in condition for further operation.

From the foregoing, taken in connection with the accompanying drawings, it will be obvious that although the invention is of comparatively simple and inexpensive construction, it will be highly efficient and durable. Since probably the best results are obtained by the specific construction shown and described, this construction constitutes the preferred form of the improved machine. It is to be understood, however, that within the scope of the invention as claimed, numerous changes may be made without sacrificing the principal advantages.

I claim:

1. In a machine for applying coatings, the combination of a carrier having means for holding the article to be coated, means above said carrier for containing the coating liquid, an outlet spout for said containing means, means in said spout for forcing the coating liquid therefrom onto the article to be coated, and means for automatically operating said last named means as said carrier travels beneath said spout.

2. In a machine for applying coatings, the combination of an inclined trackway, a carriage movable along said trackway and having means for holding the article to be coated, means above said carriage for applying the coating to the article, a second inclined trackway, a weighted car movable oppositely from said carriage and mounted on said second trackway, and means connecting said car and carriage whereby downward movement of the former will pull the latter upwardly along its respective trackway.

3. In a machine for applying coatings, the combination of a carrier having means for holding the article to be coated, means above said carrier for applying the coating material to said article as the carrier moves thereunder, said means including a delivery

spout and a pusher for moving the coating fluid from said spout, and means on said carrier for operating said pusher.

4. In a machine for applying coatings, the combination of a carrier having means for holding the article to be coated, a tank above said carrier to contain the coating fluid, said tank having a delivery spout, a transverse bar extending across said spout for moving the coating material therefrom, arms rising from said bar, a rock shaft carrying said arms, an operating arm extending from said rock shaft, and means on said carrier for swinging said operating arm as said carrier moves under said tank. 80

5. In a machine for applying coatings, the combination of a carrier having means for holding the article to be coated, a tank above said carrier to contain the coating fluid and having an outlet spout, a member 85 depressible into the fluid in said spout for starting the flow of said fluid from the end of the spout, and means on said carrier for operating said member as said carrier moves under said tank. 90

6. In a machine for applying coatings, the combination of a carrier having means for holding the article to be coated, a tank above said carrier to contain the coating fluid and having an outlet spout, a member depressible 95 into the fluid in said spout for starting the flow of said fluid from the end of the spout, arms rising from said member, a rock shaft carrying said arms and extending transversely across the spout, an operating arm projecting from said rock shaft, and means on the carrier for actuating said operating arm as said carrier moves beneath the tank. 100

7. In a machine for applying coatings, the combination of a carrier having means for holding the article to be coated, a tank above said carrier to contain the coating fluid, said tank having an outlet spout, means in said spout for raising the level of fluid therein, means for pushing the fluid from the end of 110 the spout, and means on said carrier for operating said fluid raising and pushing means as said carrier passes beneath the tank.

8. In a machine for applying coatings, the combination of a carrier having means for holding the article to be coated, a tank above said carrier to contain the coating fluid, said tank having an outlet spout, a transverse bar in said spout to be depressed into the fluid therein to raise the level of said fluid, 115 a second transverse bar in said spout for movement toward the end thereof to push the fluid over said end, arms rising from said first and second bars, transverse rock shafts on which said arms are carried, operating arms projecting from said rock shafts, and means on the carrier for actuating said operating arms as said carrier passes under said tank. 120

9. In a machine for applying coatings, 130

- the combination of a carrier having means for holding the article to be coated, a tank above said carrier divided by a horizontal partition into an upper reservoir compartment and a lower working compartment, the latter having an outlet spout, a valve for controlling communication between the two compartments, and means for opening said valve automatically as the carrier passes beneath the tank.
10. In a machine for applying coatings, the combination of a carrier having means for holding the article to be coated, a tank above said carrier divided by a horizontal partition into an upper reservoir compartment and a lower working compartment, the latter having an outlet spout, a valve for controlling communication between the two compartments, means for opening said valve automatically as the carrier passes beneath the tank, means for raising the level of fluid in said spout, and means for operating said level raising means as said carrier passes beneath the tank.
15. 11. In a machine for applying coatings, the combination of a carrier having means for holding the article to be coated, a tank above said carrier divided by a horizontal partition into an upper reservoir compartment and a lower working compartment, the latter having an outlet spout, a valve for controlling communication between the two compartments, means for opening said valve automatically as the carrier passes beneath the tank, means in the spout for pushing the coating fluid from the delivery end thereof, and means on the carrier for operating said pushing means as said carrier passes beneath the tank.
20. 12. In a machine for applying coatings, the combination of a carrier having means for holding the article to be coated, a tank above said carrier divided by a horizontal partition into an upper reservoir compartment and a lower working compartment, the latter having an outlet spout, a valve for controlling communication between the two compartments, means for opening said valve automatically as the carrier passes beneath the tank, means for raising the level of fluid in the aforesaid spout, means for pushing said fluid from the delivery end of said spout, and means operated from the
- carrier for actuating said fluid raising means and said pushing means as the carrier passes under said spout.
25. 13. In a machine for applying coatings, the combination of upper and lower trackways movable bodily between horizontal and inclined positions, a carriage mounted on the upper trackway and having means for holding the article to be coated, means above said upper trackway for applying the coating fluid, a weighted car mounted on the lower trackway and movable oppositely from said carriage, and means connecting said car and carriage to cause descent of the former to pull the latter upwardly along its respective trackway.
30. 14. In a machine for applying coatings, the combination of a pair of side frames, an inclined track mounted between said frames for movement to and between horizontal and inclined positions, a carriage mounted on said track for carrying the article to be coated along the same, a tank above said track to contain the coating fluid, said tank having an outlet spout and being mounted for vertical and horizontal adjustment and for tilting movement, and means for locking said tank in adjusted position.
35. 15. In a machine for applying coatings, the combination of a pair of side frames, an inclined track mounted between said frames for movement to and between horizontal and inclined positions, a carriage mounted on said track for carrying the article to be coated along the same, a tank above said track to contain the coating fluid, pivot pins projecting outwardly from the sides of said tank, slides having means receiving said pins rockably therein, tracks supporting said slides for horizontal movement, means for holding said tracks in vertically adjusted position, and means for holding said tank against tilting movement around said pivot pins.

In testimony whereof I, LIBBIE M. KLOCK, administratrix of the estate of ADAM I. KLOCK, have hereunto set my hand in the presence of two subscribing witnesses.

LIBBIE M. KLOCK,
Administratrix of Adam I. Klock, deceased.
